CARBURETOR

Edmund E. Hans, Detroit, Mich.

Application June 29, 1945, Serial No. 602,218

5 Claims. (Cl. 261—18)

1

This invention relates to improvements in carburetors. At the present time it is customary to make a carburetor so that the amount of fuel which passes from the float chamber to the mixing chamber varies proportionately to the amount of suction exerted in the intake manifold. However the volume of fuel required for economical operation does not vary throughout the entire driving range in exactly this ratio, and it is for that reason that such low mileage is obtained when driving at high speeds.

It is an object of this invention to provide a carburetor including automatic means actuated by the suction of the intake manifold for regulating the flow of fuel from the float chamber to the mixing chamber so that the flow does not vary in direct proportion to the suction exerted at all times. This automatic regulation is obtained by movement of a cam which actuates a valve, and the cam is so formed that, as it is turned by a change in the amount of suction exerted, the valve opening is always such that the proper amount of fuel passes to the mixing chamber for satisfactory and economical operation of the motor; and to this end it is frequently necessary to provide the contact face of the cam with a sequence of steps which are irregularly spaced relative to the cam axis. Moreover by the simple expedient of substituting one cam for another the fuel flow can be set over the entire driving range to best suit any vehicle working under any particular set of driving conditions, such as a heavy truck operating over mountain roads.

Another object of the invention is to provide a carburetor including two float chambers and two similar automatic regulating means for controlling the flow of fuel from one chamber and the flow of alcohol or other suitable anti-knock liquid from the other, so that the fuel is economically fed to the mixing chamber throughout the entire driving range, and only when the suction exerted in the intake manifold drops below a predetermined amount is alcohol added to the fuel in just sufficient proportion to eliminate ping or knock which would otherwise occur under certain operating conditions irrespective of the fuel employed if carbon has accumulated in the engine cylinders. It is however understood that while the second float chamber and the automatic means for regulating the flow therefrom may be added to eliminate knock under all driving conditions the carburetor is not only fully operative but gives highly economical operation when only a single fuel float chamber and one automatic regulating means for the flow therefrom is employed.

2

In an internal combustion engine greatest suction is exerted in the intake manifold—which may be up to 27 inches of vacuum—when the engine is idling. Then there is no tendency for the engine to knock and nothing would be gained by adding alcohol or other anti-knock liquid to the gasoline, but when the engine is running at from 75 to 100 percent of capacity the suction exerted by the manifold drops to below 8 inches of vacuum and a knock is liable to result. Consequently it is only when the suction drops to about 8 inches of vacuum or less that my automatic means functions to regulate a flow of alcohol to the mixing chamber in just sufficient quantity to prevent a knock developing.

A further object of the invention is to provide such a carburetor with a manual adjustment for setting the mechanism by which one of the valves is operated so that the degree of opening of that valve throughout the entire suction range may be varied to suit the fuel being employed. When only one float chamber is being utilized the manual adjustment is employed for initial setting of the automatic regulating means for the flow from that chamber from which in that case fuel passes to the mixing chamber; because the amount of gasoline required depends upon the grade of fuel used. When two float chambers are provided the manual adjustment is employed to set the degree of opening of the valve through which the alcohol passes for any given degree of suction because with high octane gasoline a knock develops at a lower degree of suction than when a poorer fuel is used. Consequently while it may be necessary to begin feeding alcohol, to eliminate knock, when the suction drops to say 8 inches of vacuum, with poor gasoline, it may be possible to allow the alcohol valve to remain closed until the suction in the intake manifold drops to 6 inches when a better gasoline is being burnt.

Another object of the invention is to provide such a carburetor with another manually operable means for adjusting the automatic regulation so that either a greater or lesser suction is required to operate the valve or valves.

Yet another object of the invention is to provide such a carburetor with automatic means for preventing the air intake valve being fully opened when the alcohol float chamber is empty, because then a fully opened intake with the engine operating under full load might well result in such excessive knock as to damage the engine particularly if a low grade of fuel were being employed.

Having thus briefly stated some of the objects and advantages of the invention I will now de-

scribe a preferred embodiment thereof wherein two float chambers are provided with the aid of the accompanying drawings, in which:

Figure 1 illustrates a side elevation of the invention, and

Figure 2 is a plan view thereof.

Figure 3 is a section on the line 3-3 of Figure 1.

Figure 4 is a diagrammatic view showing the plunger at a different position in the cylinder.

Figure 5 is a section on the line 5-5 of Figure 1.

Figure 6 is a section on the line 6-6 of Figure 2.

Figure 7 shows a slight modification.

Referring to the drawings, 1 designates the body of a carburetor having float chambers 2 and 3 therein which are provided with inlet passages 4 and 5 and have floats 6 and 7 respectively therein. The flow through each inlet passage 4 and 5 into its chamber 2 and 3 respectively is controlled as shown in Figure 6 in connection with the chamber 2 by a valve 8 operated upon movement of the float 6 to open or close a port 9 in the passage 4. Formed also in the body 1 is a mixing chamber 10 to which the chambers 2 and 3 are connected through passages 11 and 11a and 12 and 12a respectively formed through the said body; the passages 11 and 12 are upwardly inclined from the chambers and the passages 11a and 12a are above the normal liquid level in the chambers. In the passages 11a and 12a valve seats 13 and 14 are provided which are adapted to be closed by needle valves 15 and 16 which are mounted in alignment and extend through opposite sides of the body 1. 17 and 18 denote springs each secured at one extremity to the body to urge the valves 15 and 16 respectively toward their closed positions.

Integral with the body 1 is a bracket 19 through which a pin 20 extends, and mounted for sliding movement upon the latter is a member 21 having a lug 22 projecting laterally therefrom. A helical spring 23 is mounted around the pin 20 between the bracket 19 and the member 21, and formed upon the outer side of the latter is a bearing face 24 against which a camming element 25 pivoted at 20a on the pin 20 is adapted to be turned so that by adjustment of the said element the spacing between the bracket 19 and the member 21 is varied. Formed integral with and projecting from one side of the bracket 19 is a lug 26.

Pivoted on opposite sides of the body 1 are bellcranks 27 and 28. Connected at its extremities to one arm 27a and 28a of each of the bellcranks is a helical spring 29 which tends to draw the outer extremities of these arms toward one another, and threaded through these arms are screws 30 and 31 the ends of which bear against the lugs 22 and 26 respectively. Pivottally supported on the other arms 27b and 28b of the bellcranks are dogs 32 and 33 respectively which are bent intermediately of their length. Mounted for rotation on the bellcrank arms 27a and 28a are cams 34 and 35 respectively having substantially semi-circular contact faces 34a and 35a against which one extremity of the dogs 32 and 33 respectively bear. The opposite ends of these dogs are seated in recesses 36 and 37 formed in the stems of the valves 15 and 16 respectively. The cams 34 and 35 are connected by a link 38 so that when the cam 35 is turned in a manner hereinafter described the cam 34 is also rotated a similar angular distance so that movement is imparted to both the valves 15 and 16.

The purpose of the camming element 25 is to adjust the opening of the valve 15 relative to that of the valve 16. For as the element is turned the member 21 is moved toward or from the bracket 19 thereby causing the bellcrank 27 to turn about its axis and impart movement to the dog 32. Thus this adjustment occurs without imparting an appreciable rotary movement to either of the cams 34 and 35.

Formed integral with the body 1 is a cylinder 40 having a piston 41 therein from which a rod 42 projects. The outer end of this rod is connected by a connecting link 42a to the cam 35. Mounted for axial movement on a sleeve 40a integral with the cylinder 40 and through which the rod 42 extends is an annularly grooved flange 44; and secured on the rod 42 adjacent its outer extremity is a flange 45. Extending between the flanges 44 and 45 around the rod 42 is a coil spring 46 which tends to retain the rod at its maximum outwardly projecting position. Mounted in the opposite end of the cylinder 40 is a tubular connection 47 which is also connected to the intake manifold (not shown) so that as suction in the latter increases the piston 41 is moved to the left—Figures 3 and 4—thereby turning the cams 34 and 35 in a clockwise direction and reducing the opening of the valves 15 and 16, or completely closing the former. Similarly as the suction of the intake manifold decreases the piston 41 is moved back toward the right—Figures 3 and 4—by the spring 46 and the cams are then rotated in the opposite direction to increase the opening of the said valves.

Integral with the cylinder 40 is a projection 64 on which a lever 65 is pivoted intermediately of its length. One extremity of this lever is bifurcated to engage opposite sides of the groove around the flange 44 and its opposite extremity has a control rod 66 pivotally attached thereto. By movement of the latter in the direction of the arrow A the closing of the valves 15 and 16 is retarded so that more alcohol is added to the mixture at any given amount of suction exerted by the intake manifold. The rod 42 is threaded from its outer extremity for engagement with the flange 45 so that the spacing between the latter and the flange 44 may be adjusted to regulate the tension of the spring 46.

Provided in the body 1 above the mixing chambers 10, and in vertical alignment therewith is a conventional air inlet passage 50 having a rod 51 extending centrally across it and an ordinary butterfly valve 52 fixed on the said rod to control the flow of air through the passage. Fixed also on the rod 51 exteriorly of the passage 50 is an arm 53 having an adjustable stop 53a projecting therefrom. Mounted on the body 1 is a solenoid 54 having leads 55 and 56 connected thereto; the lead 55 is connected to a source of power (not shown) and the lead 56 to a terminal plate 57 mounted on and insulated from the body 1. Also mounted on the latter is a terminal 58 having a resilient contact 59 projecting therefrom which tends to make a connection with the terminal plate 57, and extending from the terminal 58 is a lead 60 which is also connected to the source of power. Formed through the top of the chamber 2 is an aperture 2a through which a pin 61 on the float 6 extends. This pin 61 is so arranged that as long as there is alcohol in the chamber to support the float the pin 61 holds the resilient contact 59 in its raised position shown, but when the chamber 2 becomes empty 75 and the float 6 drops to its position indicated at

6a the contact 59 also drops and makes a connection as indicated at 59a with the terminal plate 57 whereupon the solenoid 54 is energized. When this occurs the plunger 62 is raised to its position 62a to limit the rotary movement of the stop 53 and thus the opening of the butterfly valve 51. The purpose of this arrangement is to limit the maximum amount of air which may enter the passage 50 when the supply of alcohol is exhausted and only gasoline is being fed into the mixing chamber 10, for under such circumstances a full supply of air might result in such a mixture that the motor would knock very badly, and might blow the head gasket or ruin the engine bearings.

Figure 7 shows a slight modification wherein a diaphragm 70 is substituted for the cylinder 40. This diaphragm is mounted between two spaced, apertured flanges 71 and 72 formed integral with the body of the carburetor. Extending through the flange 71 and secured at one extremity to one side of the diaphragm into which it opens is a tubular connection 47a which is also secured to the said flange 71. The opposite end of this connection 47a is connected to an intake manifold (not shown). Mounted on and projecting from the opposite side of the diaphragm is a rod 42b which is axially movable through the flange 72 so that the length of the diaphragm is controlled and the rod 42b is moved through the flange 72 by suction exerted by the manifold.

As already stated one float chamber and the parts required for automatically regulating the opening of the valve between the float chamber and the mixing chamber may be dispensed with if it is merely desired to obtain economical operation and the anti-knock feature is not to be taken into consideration. Then the float chamber retained is the one the setting of the valve opening from which may be manually adjusted through movement of the camming element 25 and that float chamber is then used for gasoline. It is of course understood that the movement which automatically regulates the flow from that chamber is still controlled by the suction in the intake manifold operating through the rod 42. In the instance shown this would involve the retention of the float chamber 2 and automatic regulation of the valve 13 operated by the rod 42 through the cam 35 and link 38 or other appropriate means, and the eliminating of the float chamber 3, so that the chamber 2 would then be used for the fuel. However when both float chambers are used the camming element is usually only provided for adjusting the automatic regulating means for the alcohol supply.

The peripheral contact faces of the cams 34 and 35 are usually not continuous curves but consist of a series of narrow lands the radial distance of each of which from the cam axis varies a few thousandths of an inch from the land next to it, though these variations are not necessarily uniform or even continuous as to direction. I usually make each land of such length that any one will contact the bellcrank 32 or 33 during the variation in the intake manifold suction which occurs within a speed range of about five miles per hour, though for a five mile per hour speed change at some speeds there is a greater variation in the amount of fuel needed for economical operation than during equal changes between other speeds.

It is also understood that the peripheral form of the two cams 34 and 35 differs. The peripheral form of the cam 35 is such that just sufficient

fuel passes from the float chamber 3 at all speeds for economical operation since the amount of suction exerted by the intake manifold varies with the speed. The irregular peripheral form of the cam 34 is such firstly to retard the opening of the valve 15 until the suction exerted by the intake manifold has dropped to a predetermined amount, after which the opening of the valve increases just sufficiently to admit enough alcohol to prevent a knock developing. In this way though alcohol is much dearer than gasoline the increased efficiency obtained reduces the total cost of the alcohol and gasoline below what the cost of the fuel would have been had gasoline alone been burnt particularly if relatively high speeds were attained, and also eliminates knock.

After the tank has been filled with gasoline the engine should be started and the camming member 25 set. This is because poorer gasoline, if burnt alone, commences to knock when the suction exerted by the intake manifold is higher, say about 8 inches of vacuum, whereas with some high octane fuels a knock does not develop until the suction exerted has dropped to say 6 inches of vacuum, and of course there is no purpose in adding alcohol until this point is reached, after which the amount of alcohol used is increased by the cam 34 as the amount of suction exerted continues to drop.

When the control rod 66 is moved the amount of the opening of both valves 15 and 16, when any given amount of suction is being exerted by the intake manifold, is increased or decreased, and of course if the opening of the fuel valve 16 is decreased in this manner the initial opening of the alcohol valve 15 is correspondingly retarded; and under certain driving conditions adjustment of this rod is advantageous.

It is also pointed out that if butane or any similar gas is to be used in place of a liquid fuel that it may be fed in the manner described from one of the so-called "float chambers" though then the float should first be removed from the chamber.

In the foregoing one embodiment of the invention has been described and shown, it is however understood that alternations and modifications may be made thereto provided they fall within the scope of the claims.

What I claim is:

1. A carburetor including a float chamber and a conduit defining an air flow pathway, said float chamber and conduit being connected by a fuel passageway, a valve in said passageway for controlling fuel flow therethrough, a bell crank lever pivotally affixed to said carburetor, a cam on the lever, an adjusting screw on the free end of one of the arms of said lever for adjusting the angular position of said bell crank lever, a valve actuating lever mounted on the other end of said bell crank lever having one end in engagement with the valve and the opposite end in engagement with the peripheral face of the cam, means responsive to fluctuations of air pressure in said air flow pathway for operating said cam and thus controlling said valve, and an abutment carried by said carburetor for said adjusting screw whereby a slight adjustment of said screw will effect a minute adjustment of the cam and valve actuating lever.

2. A carburetor including a float chamber and a conduit defining an air flow pathway, said float chamber and conduit being connected by a fuel passageway, a valve in said passageway for controlling fuel flow therethrough, a bell crank lever

pivots affixed to said carburetor, a cam on the lever, an adjusting screw on the free end of one of the arms of said lever for adjusting the angular position of said bell crank lever, a valve actuating lever mounted on the other end of said bell crank lever having one end in engagement with the valve and the opposite end in engagement with the peripheral face of the cam, means responsive to pressure fluctuations in said air flow pathway for operating said cam to control said valve, a shiftable abutment carried by the carburetor to provide a stop for said adjusting screw, a cam engaging said abutment, spring means for urging said abutment into engagement with said cam, and yielding spring means connected to said bell crank lever for holding said adjusting screw in engagement with the stop abutment.

3. A carburetor including a body having a float chamber, a conduit defining an air flow pathway having one end open to the atmosphere and the opposite end connected to the intake manifold of an internal combustion engine, said body being provided with a fuel passageway extending from said float chamber to said air pathway, a valve in said passageway for controlling fuel flow to said pathway, an arm rockably mounted on said body having a lateral extension adjacent the pivot axis thereof, a cam mounted on said arm, a valve actuating lever pivoted to said lateral extension and arranged with one end in engagement with the valve and the opposite end in engagement with the peripheral surface of said cam, an adjusting screw carried by the free end of said arm engageable with stop means carried by said body, resilient means for urging said adjusting screw into engagement with said stop means and means responsive to pressure fluctuations in said intake manifold for controlling said cam.

4. A carburetor comprising a body having a float chamber and a conduit defining an air flow pathway, one end of said conduit being open to the atmosphere and the opposite end being adapted for connection with the intake manifold of an internal combustion engine, said body being provided with a fuel flow passageway extending between the float chamber and air flow pathway, a valve in said fuel flow passageway, a control lever pivotally affixed to said body having a lateral extension at one end, a cam on said control lever intermediate the pivot point and free end thereof, a valve actuating lever pivotally affixed to said extension with one end in engagement with the valve, and the opposite end engaging the peripheral surface of the cam, an adjusting screw mounted on the free end of the control lever, a shiftable abutment engaging said

screw, means for shifting said abutment for quick actuation of said control lever, spring means for urging said control lever in a direction so that the adjusting screw will engage said abutment and means responsive to pressure fluctuations in the intake manifold of said internal combustion engine for rotating said cam.

5. A carburetor comprising a body having a pair of float chambers and a conduit defining an air flow pathway, one end of said conduit being open to the atmosphere and the opposite end being connected to the intake manifold of an internal combustion engine, said body being provided with fuel passageways extending from each of the float chambers to diametrically opposite sides of said conduit, control valves extending into said body and conduit for controlling flow of fuel from said float chambers to said air pathway, a pair of bell crank levers pivotally connected to said body, a cam pivotally attached to one arm of each of said bell crank levers, valve actuating levers supported by the other bell crank lever arm and arranged one for each of said valves with one end of said valve actuating lever in engagement with its corresponding valve and the other end in engagement with its controlling cam, means on the free ends of the bell crank arms for adjusting the angular position thereof, yielding means connecting said free arms of the bell crank levers for urging the same toward one another, adjusting means on the free ends of said arms engageable with abutment means supported by said body whereby a slight movement of said adjusting means will effect a minute adjustment of said cams and valve actuating levers, means connecting said cams for simultaneous operation and means responsive to pressure fluctuations in the intake manifold of said internal combustion engine for controlling one of said cams whereby said cams will move in unison upon pressure fluctuations in said manifold.
